(No Model.)

P. W. LAMBERT.
Strap for Satchels, &c.

No. 240,151.

Patented April 12, 1881.

Fig. 1.

Fig. 2.

Witnesses:

Otto Stafeland

William Miller

Inventor
Peter W. Lambert.
by
Van Santvoord & Hauff
his attorneys

UNITED STATES PATENT OFFICE.

PETER W. LAMBERT, OF HOBOKEN, NEW JERSEY.

STRAP FOR SATCHELS, &c.

SPECIFICATION forming part of Letters Patent No. 240,151, dated April 12, 1881.

Application filed February 23, 1881. (No model.)

To all whom it may concern:

Be it known that I, PETER W. LAMBERT, a citizen of the United States, residing at Hoboken, in the county of Hudson and State 5 of New Jersey, have invented new and useful improvements in Straps for Satchels, &c., of which the following is a specification.

This invention relates to straps for carrying satchels and other like articles; and it consists in the combination, with a satchel or the like and its frame, of a main strap connected directly to the bottom of the article, and supplemental straps connecting the main strap to the satchel-frame, so that the main strap is a 15 medium for carrying the satchel, while the strain on the article is distributed over or between its bottom and the frame. The main strap constitutes a shoulder-strap, and the supplemental straps are fastened thereto in a 20 suitable manner to form, in conjunction therewith, loops through which extends a waist strap or belt, so that while the latter assists in the support of the satchel, a simple and effective connection thereof with the other straps 25 is produced.

This invention is illustrated in the accompanying drawings, in which Figure 1 represents a perspective view. Fig. 2 is a side view, partly in section.

30 Similar letters indicate corresponding parts.

The letter A designates the body of the satchel; B, the frame; C, the main or shoulder strap; D D, the supplemental straps, and E the waist strap or belt.

35 The frame B is constructed and arranged in any usual or suitable manner, and the main strap C is connected directly to the bottom of the satchel by being drawn longitudinally around such bottom and through loops f at 40 the opposite ends thereof, the main strap being thus rendered detachable; but, if desired, the main strap may be permanently connected to the bottom of the satchel, as by stitching.

The supplemental straps D D are drawn 45 through eyes g on the frame, and fastened to the main strap C by studs h, so that the main strap is connected to the frame by their means; but, if desired, the supplemental straps may be arranged in other ways for this purpose, 50 the eyes and studs being used to render the supplemental straps, like the main strap, detachable. The length of the main strap C is such that if the same is slung over one of the shoulders and diagonally across the person the satchel is brought below the waist.

55

The waist strap or belt E extends through loops i i, which are formed by elongating the supplemental straps D D and refastening them to the main strap C, as at k, and in this example the loops are duplicated, the object 60 of this arrangement being to allow the waist-strap to be brought to a higher or lower position on the main strap.

It will be readily understood that by connecting the main strap C both to the bottom 65 of the satchel and to the frame B the strain on the article is distributed over both of these parts, and, also, that by arranging the waist-strap E in the loops i i it is a medium for assisting in the support of the satchel, while 70 its connection with the other straps is an extremely simple and effective one.

If desired, the main strap C may be shortened to form a handle, the waist-strap being in that case dispensed with; and, if desired, 75 moreover, the main strap may be terminated above the bottom of the satchel and left disconnected therefrom, except through the medium of the supplemental straps.

What I claim as new, and desire to secure 80 by Letters Patent, is—

1. The combination, with a satchel or the like, and its frame, of a main strap connected directly to the bottom of the article, and supplemental straps connecting the main strap 85 to the top of the satchel-frame, substantially as and for the purpose described.

2. The combination, with a satchel or the like, and its frame, of a main or shoulder strap, supplemental straps connecting the 90 main strap to the satchel, substantially as described, and forming loops in conjunction therewith, and a waist-strap extending through such loops, as set forth.

In testimony whereof I have hereunto set 95 my hand and seal in the presence of two subscribing witnesses.

PETER W. LAMBERT. [L. S.]

Witnesses:

W. HAUFF,
CHAS. WAHLERS.